J. E. George

UNITED STATES PATENT OFFICE.

LLOYD ESPENSCHIED, OF QUEENS, NEW YORK, ASSIGNOR TO AMERICAN TELEPHONE AND TELEGRAPH COMPANY, A CORPORATION OF NEW YORK.

HIGH-FREQUENCY MULTIPLEX SIGNALING SYSTEM.

Original application filed September 30, 1919, Serial No. 327,500. Divided and this application filed April 16, 1921. Serial No. 461,969.

To all whom it may concern:

Be it known that I, LLOYD ESPENSCHIED, residing at Queens, in the county of Queens and State of New York, have invented certain Improvements in High-Frequency Multiplex Signaling Systems, of which the following is a specification.

This invention relates to high frequency multiplex signaling systems, and particularly to a terminal circuit arrangement embodying the use of a common translating circuit adapted both to modulate transmitted telegraph impulses and to demodulate the received high frequency telegraph signals.

This application is a division of my pending application, Serial No. 327,500, filed Sept. 30, 1919, entitled "High frequency multiplex signaling systems."

In multiplex signaling systems heretofore used employing a plurality of carrier currents of various frequencies, it has been customary to insert in the transmitting and the receiving branches of the terminal circuit a translating device individual to each of the said branches. It is the primary object of the present invention to adapt the terminal circuit arrangement so that the process of modulation, demodulation and amplification of the various currents in both the transmitting and receiving branches of the terminal circuit may be performed by a single translating circuit. Although the preferable form of translating device is a single thermionic vacuum tube or a plurality of such tubes in combination adapted to function as a single unit with respect to the two branches of the terminal circuit, any well known type of translating device, such as, for example, the mechanical repeater, may be used.

Another object of this invention is to provide a circuit arrangement whereby low frequency telegraph signals or signaling impulses received over one line circuit may modulate high frequency oscillations from a source connected with the translating circuit, and the modulated high frequency oscillations may be impressed upon the transmission line circuit; and to provide for the demodulation of the high frequency signals received over the said transmission line and impressed upon the same translating

circuit. This invention also provides in combination with a circuit of the foregoing type a source of high frequency oscillations which is controlled by the frequency of the received oscillations thereby ensuring identity of frequency for the purpose of modulating and demodulating the signals.

This invention will be better understood from the following description when read in connection with the attached drawing of which Figure 1 shows one form of circuit in which the invention is embodied, Fig. 1^a shows a detailed modification of the arrangement shown in Fig. 1, and Fig. 2 shows a type of feedback oscillator adapted to be used with the general circuit shown in Figure 1.

Figure 1 shows a means for applying this invention to the transmission of telegraphic signals over wires and Fig. 1^a shows means for transmission by radio signaling system. In the figure, L₁ represents a line over which low frequency telegraphic signals may be transmitted to the terminal circuit. This line is connected with the windings of a balanced relay R₁ having associated therewith a network N₁ adapted to balance the line L₁. The armature of the relay 1 is adapted to impress impulses of opposite polarity upon the input circuit 2, which is bridged across a condenser connected into the common conductor of the input side of a duplex translating device. Connected also with the same common conductor, either directly or inductively as shown in the drawing, is a source of oscillations of carrier frequency G. Across the input side of the said translating device is a transformer T₁ for impressing high frequency received oscillations upon the said device. Connected with the common terminal of the output side of the device MD₁ is the output circuit 3, by means of which the modulated oscillations may be impressed by the triple winding transformer T₂ upon the transmission line or antenna. A network N₂ is associated with the said transformer to balance either the transmission line ML or the antenna of Fig. 1^a. Bridged across the output side of the translating device MD₁ is a differential relay R₂, the armature of which is adapted to respond to the received impulses and open and close the low frequency cir-

cuit L_1 . The relay R_1 is so designed that if the network N_1 balances the line L_1 , the impulses transmitted over the line L_1 by the operation of the armature 4 will cause no disturbance of the armature 1 in the output side of the relay.

In the operation of this circuit low frequency telegraphic signals transmitted over the line L_1 will cause the operation of the armature 1 and will apply impulses to the circuit 2 which is bridged across the terminals of the condenser K_1 . Simultaneous with the impression of the low frequency signaling impulses on the condenser K_1 high frequency carrier oscillations from the source G will likewise be impressed across the input side of the modulating and demodulating circuit MD_1 . The high frequency carrier oscillations will be modulated by the impulses impressed upon the condenser K_1 , and the modulated oscillations which appear in the output side of the modulation and demodulation circuit will be impressed by the transformer T_1 upon the output circuit 3 from which they will pass to the transmission line ML . Since the low frequency impulses and the high frequency carrier oscillations are impressed upon the common conductor of the balanced modulation and demodulation circuit, the currents resulting therefrom will flow in opposite directions through each half of the winding of the relay R_2 in the output side of the circuit and will cause no effect upon the said relay. When high frequency oscillations modulated by telegraphic impulses are received over the transmission line ML , they will be impressed by the transformer T_2 upon the receiving circuit 5 and will pass to the circuit 6 tuned to reception frequency. These modulated high frequency oscillations which are impressed across the input side of the modulation and demodulation circuit will be demodulated by means of carrier frequency oscillations impressed upon the same circuit by the source G . The resultant impulses arising from demodulation will operate the relay R_2 , and accordingly corresponding signals will be impressed upon the low frequency signaling circuit L_1 . Since the modulated high frequency oscillations arriving through the circuit 5 are impressed across the input side of the modulation and demodulation circuit, the impulses resulting from detection will produce no effect upon the circuit 3 which is coupled by means of the transformer T_3 with the common conductor in the output side of the modulation and demodulation circuit.

Figure 2 shows a novel form of generator of high frequency oscillations which is adapted to be used with the general circuit shown in Figure 1. In the arrangement shown in Figure 2 high frequency oscillations arriving over circuit 5 will be im-

pressed upon the circuit 6 tuned to reception frequency by the transformer T_1 . This circuit is tuned by means of the inductance of one of the windings of the transformer T_1 and by the capacity of the condenser K_2 . The inductance is divided between the grid and the plate circuits so as to form the feedback connection necessary in an oscillation circuit. The high frequency oscillations set up by the oscillation generator G_1 will be impressed upon the input side of the modulation and demodulation circuit as were the oscillations set up by the generator G shown in Figure 1. By means of the oscillation generator shown in Figure 2 substantial identity of frequency is obtained which insures good quality in the modulation and the detection of signals.

Although this invention has been described as being embodied in specific form and arrangement of parts, it is to be understood that it is capable of embodiment in other and different forms without departing from the spirit and the scope of the patent claims.

What is claimed is:

1. In a signaling system, the combination with a signaling circuit of a transmission circuit, networks individual to and adapted to balance the said circuits, a four-wire connecting circuit, a balanced relay adapted to respond to telegraphic impulses transmitted over the said signaling circuit, a translating circuit common to the transmitting and receiving paths of the said four-wire circuit having means to impress thereon impulses from the said relay, a source of high frequency carrier oscillations and means to modulate the high frequency carrier oscillations in accordance with the telegraphic impulses.

2. In a signaling system, the combination with a low frequency signaling circuit of a high frequency signaling circuit, a four-wire connecting circuit, a balanced relay responsive to low frequency signals from said first mentioned signaling circuit and adapted to impress them upon the said four-wire circuit, a source of carrier frequency oscillations also connected with the said four-wire circuit, means for modulating the said carrier oscillations by the said telegraph signaling impulses, and means for impressing the modulated high frequency oscillations upon the said high frequency signaling circuit.

3. In a signaling system, the combination with a low frequency signaling circuit of a high frequency transmission circuit, a four-wire connecting circuit, means responsive to telegraph currents transmitted by the said low frequency circuit to impress corresponding impulses upon the said four-wire circuit, a source of carrier current, means to impress high frequency modulated oscilla-

tions upon the said four-wire circuit, and means to modulate the carrier current in accordance with the telegraph currents and de-modulate the modulated high frequency oscillations by the carrier current, and to transmit the currents resulting from modulation and demodulation.

4. In a high frequency signaling system for the transmission of telegraphic signals the combination of a high frequency transmission circuit, a low frequency signaling circuit, a translating circuit having a source of carrier oscillations associated therewith, means for impressing the low frequency currents upon the input side of the translating circuit and for impressing the resulting modulated output currents upon said high frequency transmission circuit, and means for impressing the received high frequency oscillations upon the said input side of said translating circuit, means for beating said received oscillations and said carrier oscillations, and for impressing the impulses resulting from beating upon signaling apparatus connected with said low frequency signaling circuit.

5. In a signaling system comprising two line circuits connected by a four-wire circuit characterized by a circuit common to the transmitting and receiving paths of the said four-wire circuit and having a source of carrier current connected therewith, the

method of transmitting and receiving telegraph signals which consists in selecting telegraph impulses, selecting modulated high frequency oscillations, modulating the carrier current by the said telegraph impulses, demodulating the said modulated high frequency oscillations by means of the carrier current, transmitting the resultant currents from modulation and demodulation and preventing singing over the transmitting and receiving paths of the four-wire circuit.

6. In a translating circuit having a translating device associated therewith, the combination with means for impressing low frequency currents and modulated carrier frequency currents upon the said input side of the said translating circuit of a thermionic oscillator having its input side connected with the input side of the said translating circuit and resonant to carrier frequency and a modulating-demodulating device connected with the output side of the said oscillator and also connected with the input side of the said translating circuit whereby oscillations of carrier frequency may be supplied thereto to be modulated by the low frequency currents and to demodulate the modulated high frequency currents.

In testimony whereof, I have signed my name to this specification this 15th day of April, 1921.

LLOYD ESPENSCHIED.
